UNITED STATES PATENT OFFICE.

COLIN CAMPBELL MACMILLAN AND CHARLES ADAIR WHYTE, OF PARTICK,
GLASGOW, SCOTLAND.

AIR-FEEDING APPARATUS FOR FURNACES.

SPECIFICATION forming part of Letters Patent No. 737,644, dated September 1, 1903.

Application filed September 4, 1902. Serial No. 122,024. (No model.)

To all whom it may concern:

Be it known that we, COLIN CAMPBELL MACMILLAN and CHARLES ADAIR WHYTE, subjects of the King of Great Britain, residing 5 at Partick, Glasgow, Scotland, have invented certain new and useful Improvements in Air-Feeding Apparatus for Furnaces, of which the following is a full and complete specification, such as will enable those skilled in the 10 art to which it appertains to make and use the same.

The object of our invention is to provide an improved apparatus for use in connection with all kinds of furnaces, but more especially with steam-boiler furnaces, for preventing formation of smoke and also to save coal or reduce the amount of coal necessarily employed, a further object being to provide an apparatus of this class which may be used in 20 connection with any kind or class of fuel employed.

The invention is fully disclosed in the following specification, of which the accompanying drawings form a part, in which the 25 separate parts of our improvement are designated by the same reference characters in each of the views, and in which—

Figure 1 is a side view, partially in section, showing the application of our improved apparatus to a Cornish boiler; Fig. 2, an end view thereof; Fig. 3, a sectional side elevation of an air-distributing box which we employ, taken on the line 3 3 of Fig. 2; Fig. 4, a side view thereof; Fig. 5, a top plan view 35 of an air-distributing box shown in Figs. 3 and 4, and Fig. 6 a bottom plan view thereof.

In the drawings forming part of this specification we have shown at X an ordinary steam-boiler of the Cornish type, which is mounted 40 in the usual manner and in the front end of which is a furnace-chamber X², in which in the form of construction shown are grated members X³, beneath which is an ash-pit X⁴, at the rear end of which is the usual trans- 45 verse bridge-wall X⁵, which extends upwardly into the furnace-chamber and over which the products of combustion from the furnace-chamber pass.

In the front wall of the furnace-chamber 50 and level with the top of the grate-bars we place an air-distributing box A, which ex-

tends entirely across the furnace-chamber and which for this and similar classes of boiler-furnaces is partially inside of and partially outside of the front furnace-wall X⁶. Beneath said boiler X and passing partially around the same is an escape-flue Y for the products of combustion, and passing through said escape-flue Y and longitudinally of the boiler X are the hot-air pipes K and K², and 55 these hot-air pipes are secured at their front ends to the under side of that part of the air-distributing box A which is outside of the boiler X, as clearly shown in Fig. 1, and these pipes K and K² are curved upwardly at the rear of the boiler X and pass out of the escape-flue Y into the open air and are provided at their ends with tapering ends L and L², which are protected by covers or guards M and M², and these hot-air pipes are also 60 provided with sliding expansion-joints N and N², placed outside of the escape-flue Y and adapted to take up the expansion due to heat, and for marine and internal-combustion-chamber boilers the heating-pipes are 65 provided with sliding expansion-joints N and N², placed outside of the escape-flue Y and adapted to take up the expansion due to heat, and for marine and internal-combustion-chamber boilers the heating-pipes are 70 provided with sliding expansion-joints N and N², placed outside of the escape-flue Y and adapted to take up the expansion due to heat, and for marine and internal-combustion-chamber boilers the heating-pipes are 75 provided with sliding expansion-joints N and N², placed outside of the escape-flue Y and adapted to take up the expansion due to heat, and for marine and internal-combustion-chamber boilers the heating-pipes are carried through the uptake.

At Z we have shown an ordinary steam-drum having a supply-pipe Z², and connected with this supply-pipe is a small pipe P, which is provided with a valve R, and at the outer 80 end of the pipe P are two nozzles O and O², adjusted centrally with the orifices of the tapering ends L and L² of the hot-air pipes K and K², and pivotally secured to the valve R is a rod S, which passes to the front of the 85 boiler X and is adapted to be operated as shown at S² or in any other desired manner.

At the front of the air-distributing box A we provide a number of small conical holes for the admission of air, and in the top wall 90 of the box A are a plurality of openings B, which are provided with an inwardly-swinging door B², and this door is secured to a transverse rod B³, to the end of which, outside of said distributing-box, is secured a 95 lever B⁴, and the door B² is adapted to close the openings B in the operation of our invention. We also provide in the bottom wall of the distributing-box A a plurality of openings C, provided with an outwardly-swinging door C², secured to a transverse rod C³, which is 100 provided at its outer end with a lever C⁴, which

is adjacent to the lever B^4 , and the doors B^2 and C^2 are adapted to be operated by the rods B^3 and C^3 and the levers B^4 and C^4 , respectively. The openings B communicate to that 5 part of the furnace-chamber over the fire-grates X^3 , while the openings C communicate with that part of the furnace-chamber under the fire-grates X^3 . On the outer end of the air-distributing box A and adjacent to the 10 levers B^4 and C^4 is pivotally mounted a disk F , provided with a projecting arm G , and on the outer face of the disk F are two pins D and E , which are preferably near the edge of said disk and radially opposite each other, 15 and operating in connection with said pins D and E are two bars D^2 and E^2 , which are pivoted at their other ends to the levers B^4 and C^4 , respectively. We also pivot to the disk F , near the edge thereof, an upwardly- 20 directed arm V , which passes slightly above the top of the distributing-box A and is held in position on said distributing-box A by guides V^2 , and the upper end of the arm V , which projects above the distributing-box A , 25 is preferably wedge-shaped, and all of this construction is clearly shown in the drawings.

Pivoted to the arm G of the disk F is a downwardly-directed piston-rod T , on the lower end of which is secured a piston 30 T^2 , which closely fits into a dash-pot U , and the piston T^2 is provided with a small conical hole passing therethrough, the larger end of which is at the top, and on one side of the dash-pot U are two openings W and W^2 , one 35 at the top and the other at the bottom thereof, and these openings W and W^2 are connected by a pipe W^3 , provided with a check-valve W^4 , and in practice we partly fill the dash-pot U with oil, and the weight of the piston 40 descending causes part of said oil to ooze through the opening in the piston T^2 and remain over said piston.

On the front wall X^6 of the boiler X we provide a furnace-door X^7 , the bottom of which 45 passes closely over the top wall of the distributing-box A , and the lower edge of the furnace-door X^7 is adapted to engage the wedge-shaped top of the arm V . We also provide the usual ash-pit doors or slides Q , 50 which may be provided with air openings or vents, if desired. The hot-air pipes K and K^2 may also be provided with fans or blowers at their rear ends, if desired, instead of the steam-jet for the purpose of forcing the 55 draft, although we have not shown them in the drawings.

The fires are started and steam raised in the usual manner, and when the furnace is charged with green coal a greater amount of 60 air is necessary over the top of the fire in order to consume the rising hydrocarbon gases, and when the furnace-door X^7 is opened the lower edge thereof strikes against the inclined surface of the arm V , which is there- 65 by forced downward, and thereby operates the disk F , to which it is pivoted, and the

bars D^2 and E^2 are also moved thereby, and with said arms D^2 and E^2 the levers B^4 and C^4 , which are pivoted thereto, and the doors B^2 and C^2 are operated by said levers B^4 and C^4 , the doors B^2 opening downwardly into the distributing-box A and the doors C^2 closing partly, as shown in dotted lines in Fig. 3. As the disk F is partially revolved in the 70 operation just described, the arm or handle G integral therewith is raised and carries with it the piston-rod T and piston T^2 , secured thereto, and the oil which was above the piston T^2 flows therefrom into the pipes W^3 and back into the dash-pot U through the check- 75 valve W^4 . The fireman at this time or previously operates the valve R by means of the rod S and allows steam from the supply-pipe to pass into the hot-air pipes K and K^2 , and this steam forces air through said pipes, and, 80 as hereinbefore described, the pipes K and K^2 being placed within the escape-flue Y the air passing through said pipes is heated by the time it reaches the air-distributing box A and passing through the openings B into 85 the furnace-chamber above the fire-grates combines eagerly with the hydrocarbon gases rising from the green fuel when the fire is charged, and the heating of the air as just described is necessary to the proper operation of our invention, and the hot air not only mixes with the gases rising from the green coal, but it also forms a layer of such air between the gases and the relatively cold plates of the top of the furnace-chamber, and the gases are therefore consumed before reaching said plates by combining with said hot air and are not condensed by the said plates into the form of soot, and the formation of smoke is thereby prevented. 90

The reason for the construction of the dash-pot U and the piston T^2 is that while it permits of the rapid raising of said piston the descent of the same is necessarily slow, as the oil must ooze through the conical hole in the piston T^2 before gravity can bring said piston to its lowest position, and as the operation is gradual the reversal of the position of the doors B^2 and C^2 is necessarily gradual, and the hot air therefore passes over the fire-grates and combines and consumes the gases rising from the fresh coal until the piston T^2 is entirely down, when the doors B^2 are closed and the doors C^2 are open, and the hot air passing under and through the fire-grates 100 X^3 forms a draft and assists the natural draft of the escape-flue Y , and this supplemental draft may be regulated or shut off entirely by the rod S and valve R , as will be readily seen, and this operation may be made automatic, if desired. 105

This apparatus is simple in construction and operation and is also comparatively inexpensive, and by means thereof the production of carbon-laden smoke is almost if not 110 entirely prevented, the amount of coal used is reduced to a minimum, and the efficiency 115

of a boiler as a steam-generator is thus largely increased.

Having fully described our invention, what we claim as new, and desire to secure by Letters Patent, is—

1. In an apparatus for supplying air to the furnace-chamber of a boiler, an air-box in communication with the furnace-chamber above and below the grate, and provided with doors controlling said communication, and means for operating said doors consisting of levers in connection with said doors, a disk mounted on said air-box, bars connecting said levers with said disk, an arm in connection with and adapted to operate said disk and provided with a wedge-shaped end projecting over the top of said air-box and adapted to be operated by the door of said furnace-chamber, a dash-pot, a piston movable there-
15 in, and connected with said disk and provided with a conical hole through said piston, and a pipe connecting the top and bottom of

the dash-pot and provided with a check-valve substantially as shown and described.

2. A coal-saving and smoke-preventing apparatus for use in connection with a boiler comprising an air-distributing box located in the front of the furnace-chamber, air-pipes in connection therewith, means for heating and forcing air through said pipes into said box, doors opening from said box into the space above and below said grate, and devices for automatically and alternatively operating said doors, substantially as shown and described. 25 30 35

In testimony that we claim the foregoing as our invention we have signed our names, in presence of the subscribing witnesses, this 13th day of August, 1902.
